UNITED STATES PATENT OFFICE.

EDWIN D. HARRIS, OF SYCAMORE, ILLINOIS, ASSIGNOR OF ONE-HALF TO ARTHUR A. MUELLER, OF SYCAMORE, ILLINOIS.

INSULATOR.

1,151,179.

Specification of Letters Patent. Patented Aug. 24, 1915.

Application filed April 25, 1914. Serial No. 834,403.

To all whom it may concern:

Be it known that I, EDWIN D. HARRIS, a citizen of the United States of America, residing at Sycamore, in the county of Dekalb 5 and State of Illinois, have invented new and useful Improvements in Insulators, of which the following is a specification.

This invention relates to improvements in insulators and has particular application to 10 an insulator wherein the use of tie wires and the like will be eliminated.

In carrying out the present invention, it is my purpose to provide an insulator of the class described whereby electric current carrying conductors may be supported upon 15 poles and the like and insulated therefrom without the use of tie wires or the like.

It is also my purpose to provide an insulator which will hold the wires securely and 20 effectively, which may be readily and quickly connected with the wire and which may be manufactured and marketed at a minimum expense.

With the above and other objects in view, 25 the invention consists in the construction, combination and arrangement of parts hereinafter set forth in and falling within the scope of the claims.

In the accompanying drawings; Figure 1 30 is a view in elevation of an insulator constructed in accordance with the present invention. Fig. 2 is a vertical central sectional view therethrough. Fig. 3 is a top plan view thereof.

Referring now to the drawings in detail, 35 1 designates the body of an insulator which, in the present instance, is circular in cross section and has one end thereof formed with a threaded bore 2 adapted to receive a pin carried by the cross arm of the pole or similar support. Formed in the body 1 adjacent to the upper end thereof is a substantially V-shaped slot 3 opening onto the side of the body and preferably inclined upwardly, 40 while contiguous the bottom wall of the slot 3 and communicating therewith is a groove 4 having the side wall thereof connected with the lower wall of the groove forming a shoulder 5. Formed in the body 1 coaxial 45 therewith is a bore 6 having one end thereof opening onto the top of the body and the lower end merging into the groove 4 at the apex of the slot 3 and communicating with a passage 7 formed in the body at right

angles to the bore 6 and opening onto the 55 side wall of the body at a point behind the apex of the slot 3. The passage 7 is preferably inclined downwardly to facilitate drainage, while the top and bottom walls of the slot 3 are formed with alining grooves 60 7', 7" merging into the apex of the groove to receive a tool.

In practice, the wire is placed in the mouth of the slot 3 and a tool employed to force the portion of the wire within the slot 3 over 65 the lower wall of such slot so that such portion of the wire will conform to the configuration of the slot. When the apex of the V-shaped portion of the wire is disposed within the bore 6 a tool is passed into the 70 latter thereby forcing the wire into the groove 4 and behind the shoulder 5. Thus, the wire is securely held within the slot and the use of tie wires and the like eliminated. When it is desired to release the wire a tool 75 is inserted into the passage 7 to elevate the wire out of the groove 4 and beyond the shoulder 5 whereby the wire may be readily slipped out of the slot 3.

From the foregoing description taken in 80 connection with the accompanying drawings, the construction, mode of operation and manner of employing my invention will be readily apparent. It will be seen that I have provided an insulator whereby electric 85 current carrying conductors and the like will be securely held in position without the use of tie wires and analogous devices and whereby the wire may be readily connected with and disconnected from the insulator. 90

I claim:

1. An insulator comprising a body having a substantially V-shaped slot formed therein and opening onto the side thereof, and a groove contiguous the bottom wall of the 95 slot and communicating with the latter whereby a shoulder is formed to hold the wire, said body being further formed with a bore coaxial therewith and opening onto the upper end thereof whereby access may be 100 had to the wire to press it over said shoulder.

2. An insulator comprising a body having a substantially V-shaped slot formed therein and opening onto the side thereof, and a groove contiguous the bottom wall of the 105 slot and communicating with the latter whereby a shoulder is formed to hold the wire, said body being further formed with a

bore coaxial therewith and opening onto the upper end thereof whereby the wire may be passed over said shoulder, and with a passage communicating with said groove whereby access may be had to the wire to lift it off of said shoulder.

In testimony whereof I affix my signature in presence of two witnesses.

EDWIN D. HARRIS.
